INVENTOR.
J. E. NEEDHAM

BY

Richard D. Owen
ATTORNEY.

UNITED STATES PATENT OFFICE.

JANE E. NEEDHAM, OF BROOKLYN, NEW YORK.

SPOOL HOLDER.

Application filed August 2, 1922. Serial No. 579,274.

To all whom it may concern:

Be it known that I, JANE E. NEEDHAM, a subject of the King of England, residing at Brooklyn, in the county of Kings and 5 State of New York, have invented certain new and useful Improvements in Spool Holders, of which the following is a specification.

This invention relates to devices for suspending balls or spools of yarn, thread, cord or twine or the like so as to permit of the convenient and easy removal thereof as when an individual is engaged in knitting, crocheting, tatting or other work.

10 The primary object of my invention is the provision of a simple yet very convenient spool or ball holding device which can be easily carried and suspended from the arm or wrist of the individual so that the 20 thread or yarn, for instance, may be unwound as required during the act of knitting or crocheting and which will not interfere with the speedy operation of the individual when engaged in such work.

15 Another and very important object of my invention is the provision of a device of the character above described which permits of the suspension of the ball or spool of thread or yarn and which may be removed 30 from the top or bottom of the spindle so as to permit of the ready use of thread or yarn of different colors without interference.

I accomplish the above objects and others in the accompanying drawings, wherein—

35 Figure 1 is a side view of a holder embodying my invention.

Figure 2 is a detailed view showing the wooden core or which the thread or yarn is wound and the spindle for holding the 40 same.

Figure 3 is a detailed view showing the wrist or arm engaging portion of the spindle and its distorted position whereby the spool may be removed therefrom.

45 Figure 4 is a detailed view of the pivoted connection at the end of the spindle.

Referring now to the drawings wherein like reference characters designate corresponding parts throughout the several views,

50 5 designates a spindle preferably constructed of a flexible or distortable composition preferably of celluloid or metal and which is bent to form a ring or arm engaging loop 6, the free end 7 of which is spaced considerably from the spindle 5 so as to permit 55 of the easy insertion of a ball or spool of

thread or yarn or the removal thereof as indicated in dotted lines by Figure 3, in addition permitting the distortion of the wrist engaging portion so that it may be slipped 60 up on the arm of the individual.

The spindle 5 is adapted to be passed through the ball 8 of the wooden core 9 on which is wound the thread or yarn 10 and at the extreme end 11, I have provided a 65 stop 12 pivoted as at 13, which stop forms an overlapping joint with the end of the spindle so that it will lie in perfect alignment therewith when passing through the core of the spool and which stop may be rotated on its pivot to lie at right angles to the spindle 5 and thus maintain the spool in position. A disc 15 having a central recess 16 may also be provided and in addition, 70 not only forms a stop for the wooden core 9 of the spool or the paper core of a ball of wool or yarn, but permits of the printing or stamping of any advertising matter on the disc as may be desired such as the name 75 of the individual or the particular company manufacturing the wool or yarn above referred to.

So far as I am aware, I am the first to construct a spool or ball holding device which permits of the removal of the same from either end of the spindle and one wherein the wrist or arm engaging portion is formed integral with and is a continuation of the spindle proper. While I have suggested the 85 use of celluloid or metal as being the preferred material for constructing a spool or ball holding device as above set forth, I do not wish to be unnecessarily limited or restricted to the use of such material only 90 since it will be readily recognized that the cost of producing such devices is dependent upon the material used and consequently the same idea may be embodied by shaping and bending the wooden or bamboo spindle or even a bone spindle as manufactured 95 100 necessities may require.

While I have illustrated and described my invention with some degree of particularity, I realize that in practice various alterations 105 therein may be made. I therefore reserve the right and privilege of changing the form of the details of construction or otherwise altering the arrangement of the correlated parts without departing from the spirit of the invention or the scope of the 110 appended claims.

Having thus described my invention, what

I claim as new and desire to secure by United States Letters Patent is:—

1. As a new article of manufacture, a holder for spools, balls and the like comprising a ball and spool receiving spindle, a ball and spool stop carried by the lower end of the spindle, and an open wrist receiving bracelet having one end formed integral with the upper end of the spindle, 10 and its opposite end gradually tapered, the bracelet being flexible, as and for the purpose specified.

2. As a new article of manufacture, a holder for spools, balls and the like comprising a ball and spool receiving spindle, an annular stop plate slidably associated with the lower end of the spindle, a pivoted stop connected with the lower end of the spindle for holding the plate against accidental movement, and a flexible open wrist receiving bracelet formed on the upper end of the spindle. 15 20

In testimony whereof I affix my signature.

JANE E. NEEDHAM. [L.S.]
